SKIRT PORTION FOR A SHUTTLECOCK OR SIMILAR ARTICLE

Louis Sametz, Westport, Conn.

Application October 3, 1952, Serial No. 21,676

Term of patent 14 years

(Cl. D34—5)

To all whom it may concern:

Be it known that I, Louis Sametz, a citizen of the United States, residing at Westport, State of Connecticut, have invented a new, original, and ornamental Design for a Skirt Portion for a Shuttlecock or Similar Article, of which the following is a specification, reference being had to the accompanying drawings, forming a part hereof.

Fig. 1 is a perspective view of a skirt portion for a shuttlecock or similar article, showing my new design;

Fig. 2 is a top plan view thereof;

Fig. 3 is a bottom plan view thereof; and

Fig. 4 is a side elevational view thereof.

The broken line showing of a shuttlecock nose in Fig. 4 is for illustrative purposes only.

I claim:

The ornamental design for a skirt portion for

a shuttlecock or similar article, substantially as shown and described.

LOUIS SAMETZ.
